WALL CONSTRUCTION

John Dahlin, Minneapolis, Minn.

Application May 28, 1947, Serial No. 750,979

1 Claim. (Cl. 98--31)

1

My present invention relates generally to building wall structures and, more specifically, to foundation walls of hollow block construction.

The primary object of my invention is the provision of a wall having horizontal and vertical passages therein which, in cooperation with the integrally-formed and cooperating chimney flue construction, will eliminate moisture and dampness usually found in basement or subterranean walls.

Another object of my invention is the provision of a wall of the type immediately above-described, which may be constructed of relatively inexpensive building blocks or the like, which is durable, and which in use will eliminate dampness both within the wall and within the space circumscribed by the wall by utilizing the natural draft of a chimney to circulate air within the wall.

The above and other objects and advantages of my invention will become apparent from the following detailed specification, appended claims, and attached drawings.

Referring to the drawings, wherein like characters indicate like parts throughout the several views:

Fig. 1 is a fragmentary perspective view of a wall embodying my invention;

Fig. 2 is a fragmentary view partly in section, taken on the line 2--2 of Fig. 1;

Fig. 3 is a view corresponding somewhat to Fig. 1, but showing only two horizontal tiers of blocks;

Fig. 4 is an enlarged perspective view of an end or a corner block of the type used in my wall construction;

Fig. 5 is a perspective view of an intermediate block used in my improved wall construction;

Fig. 6 is a perspective view of a chimney flue-forming block; and

Fig. 7 is a perspective view of a different type of chimney flue-forming block.

Referring with greater particularity to the drawings, the letter *a* indicates a suitable foundation, such as basement flooring, upon which is laid the wall structure, identified in its entirety by the numeral 1. Preferably and as shown, my novel wall is primarily composed of intermediate blocks 2 and end or corner blocks 3. Each block 2 is a monolithic structure, preferably formed from concrete or the like and comprising laterally-opposed longitudinally-extending side walls 4 joined by vertically-extending transverse partitions 5. The side walls 4 and the partitions 5 define vertical passages 6, the purpose of which will hereinafter become apparent. The partitions 5 are, at one end, each flush with the ad-

2

jacent edge portion of the walls 4. Their other ends are formed with segmental notches or concavities, as indicated at 7.

The end partitions 5 of each block 2 are spaced inwardly from the ends of the side walls 4 so that when two or more of the blocks 2 are laid in end-to-end relation, a still further vertical passage 6 is formed between said blocks.

The end or corner blocks 3 are composed of the same material as the blocks 2 and comprise longitudinally-extending side walls 8 and 9 and an end wall 10. Longitudinally-spaced vertically-extending transverse partitions 11 between the walls 8 and 9 are flush with one longitudinal edge of the walls 8 and 9 at one of their ends and are formed with segmental notches 12 at their other ends. The side walls 8 and 9, the end wall 10, and the partitions 11 define vertical air passages 13. It will be noted that the end wall 10 is flush at both of its ends with the longitudinal edges of the side walls 8 and 9 and, as shown particularly in Fig. 4, side wall 8 is provided adjacent one end with a segmental notch 14, which lies in the same horizontal plane but at right angles to the notches 12 in the partitions 11.

The wall structure 1 is further made up of a plurality of flue-forming blocks 15 and 16. As shown in Fig. 6, the block 15 is rectangularly tubular in form being provided with a vertical passage 17 therethrough. The blocks 16 are similar in shape to the blocks 15, but are further provided with segmental notches 18 in one side wall thereof which extend from the vertical passage 17 therethrough to the exterior of the block.

As shown in Figs. 1 to 3 inclusive, the bottom tier of wall 1 is made up of blocks 2 and 3, laid on the floor *a* in an inverted position, and a block 16 also in an inverted position. This arrangement creates a horizontal segmental passage 19, defined by the floor *a* and the segmental notches 7, 12, 14, and 18. The bottom tier is laid with one of the end or corner blocks 3 abutting the inverted flue-forming block 16 and having its segmental notch 14 opening into the room or space which will be at least partially defined by the finished wall. It will be here noted that there is no horizontal passage between the flue-forming block 16 and the adjacent block 3.

The second tier is laid with the blocks 2 and 3 and a flue-forming block 16 in a normal upright position. The third tier, however, is laid with the blocks 2 and 3 and a flue-forming block 16 in an inverted position in the same manner as the lowermost tier. The segmental notches 7, 12, 14, and 18 thus assume opposed positions to form

therebetween a substantially circular horizontal passage 20.

It is obvious that, in properly laying a wall of the type herein described, it is necessary to have end or corner blocks 3 both of the right and left hand types, wherein the notch 14 is transposed from the wall 8 to the wall 9. In other words, some of the blocks 3 would have notches 14 in the walls 8 thereof and others would be provided with notches 14 in the wall 9 thereof adjacent the end wall 10 so that, whether the block is laid at one side of the corner or the other, or whether in an inverted or upright position, the notch 14 may be made to properly register with the notches 7 in the adjacent intermediate blocks to form continuous horizontal passages 19 or 20.

As is usually necessary in the building of wall structures such as herein described, the different blocks 2 are in a staggered vertical relationship with the central portion of one of the blocks 2 resting upon the end portions of two abutting blocks in the tier directly beneath. In order to utilize the flue-forming blocks 15 and 16, it is, therefore, necessary to provide intermediate blocks similar to the blocks 2, but of approximately one-half the length thereof. Usually these blocks are provided by simply dividing one of the blocks 2 into two substantially equal parts, and I have indicated these shorter blocks by the numeral 2'.

The fourth and fifth tiers of the wall 1 are similar to the second and third with the exception that flue-forming blocks 15 are substituted for the flue-forming blocks 16 so that the horizontal passage 20 between the fourth and fifth tiers will have no direct opening into the vertical passage 17. Subsequent tiers are preferably laid in the same manner as the fourth and fifth tiers. However, attention is called to the fact that at a suitable height from the floor, a pair of flue-forming blocks 16 are used, one being in an upright position and the one immediately thereabove in an inverted position so that the notches 18 therein form a substantially circular outwardly-opening passage 21 for the reception of an 45 exhaust stack of a furnace, not shown.

The wall 1 may be built to any suitable height and finished off in suitable manner without interference with the function thereof.

It will be apparent that a wall built as above provided will have therein a network of interconnecting horizontal and vertical passages. Furthermore, my arrangement of opening 14 to atmosphere and opening 18 to the flue 17, insures a circulation of air through the entire wall. Thus, the natural draft in the flue 17 tends to pull air through the openings 18 in the lower flue blocks 16 from the interior of the wall 1, causing a current of air to enter the interior of the wall 1 through the opening 14 in the block 3 adjacent the flue block 16 in the lowermost tier. The result of circulation of air through the interior of the wall 1 will evaporate any moisture which will tend

to accumulate therein and keep the wall and the space defined thereby in a dry and healthy condition.

It should be obvious that, in the construction 5 of my novel wall, a somewhat different arrangement of the blocks 2, 2', 3, 15, and 16 than that shown in the accompanying drawings, may be had without avoiding the spirit of the invention as expressed in the appended claims. Particularly is this true of the location of openings 14, 18, or 20, the precise location of which is not important.

What I claim is:

15 A building wall circumscribing a given area and formed from tiers of blocks, said wall being made up primarily of blocks having laterally-opposed longitudinally-extending side walls joined by vertically-extending longitudinally-spaced partitions, said side walls of the partitions defining vertical passages therethrough, said partitions at one end being flush with the adjacent edges of the side walls and at their opposite ends being formed with segmental notches, said blocks being positioned with respect to each other in 20 said wall to provide horizontally-extended passages between alternate pairs of tiers and vertically-extended wall passages which communicate with said horizontally-extended passages, a chimney flue in said building wall extending upwardly from one of the lowermost tiers of said wall and having an opening in the intermediate portion thereof adapted to receive the exhaust stack of a furnace, said chimney flue having a lateral opening at one side communicating with 25 the inter-connecting vertical and horizontal passages in said wall, said wall being provided with a lateral opening adjacent its base communicating with atmosphere within the area defined by the wall, said opening being located on the side of 30 the flue opposite the opening within the side of the flue connecting with the inter-connecting vertical and horizontal passages in the wall.

JOHN DAHLIN.
